MACHINE FOR FINISHING THE PILE SURFACE OF CARPETS AND RUGS

Richard G. Knowland, Longmeadow, Mass., and Wellesley B. Cooper, Amsterdam, N. Y., assignors to Bigelow-Sanford Carpet Co., Inc., Thompsonville, Conn., a corporation of Massachusetts

Application November 18, 1931, Serial No. 575,766

15 Claims. (Cl. 26—2)

This invention relates to machines for treating and finishing the pile surface of carpets and rugs to more effectively eliminate the "row" appearance of the pile forming tufts and provide 5 a better coverage for the backing fabric.

In pile carpets and rugs as now commonly woven the pile surface is formed by rows of twisted pile forming tufts secured to and projecting from a backing fabric. The row arrangement of 10 the pile forming tufts remains more or less objectionably apparent in the finished carpet or rug and the backing fabric tends to "grin through", thus further detracting from the appearance of the carpet or rug in use.

15 The pile forming tufts are usually composed, in whole or in part, of twisted woolen fibres which possess felting characteristics when subjected to a rubbing action in the presence of heat and moisture, and one of the important features of 20 the present invention consists in a pile tuft heating and moistening means and a pile rubbing platen having a rubbing surface adapted to act upon the pile tufts in a plane inclined to the plane of 25 the carpet or rug to thereby vary the pressure of the rubbing surface upon the pile during the movements of the platen. The effect of the alternate increase and decrease of the platen pressure is to first separate the fibres of the pile forming tufts and second to permanently interlock or 30 felt together the end portions of the fibres in adjacent tufts that the "row" appearance of the pile may be eliminated and a more complete coverage of the backing fabric secured.

In its broader aspect a feature of the invention 35 consists in feeding the carpet or rug through the machine by appropriate feeding mechanism and to tension a strip of the carpet or rug opposite the platen or rubbing surface so that during the action of the platen the carpet may yield under 40 the varying pressures of the platen surface while the tension of the strip of carpet or rug serves to maintain the pile surface of the latter in coacting relation with the rubbing surface.

In effectively separating the fibres of the pile 45 forming tufts and then permanently interlocking the fibres of adjacent tufts, the present invention contemplates a relative adjustment between the plane of the carpet or rug and rubbing surface to first separate the fibres of the pile forming tufts and second to permanently interlock or

55 felt the fibres of adjacent tufts together. Where the plane of action of the rubbing surface and the plane of the carpet or rug is angularly arranged, as contemplated by the present invention, an alternate increase and decrease of pressure results between the rubbing surface and the pile forming tufts and as a convenient means for carrying this feature into effect the present invention provides for an angular change in the relation of the carpet or rug and rubbing surface and, as 60 shown in the present instance of the invention, this is effected by mounting the rubbing platen for angular adjustment relative to the plane of the carpet or rug.

The invention and novel features thereof will 65 best be made clear from the following description and accompanying drawings of one good form thereof.

In the drawings:—

Fig. 1 is a perspective view with parts broken 70 away showing a machine containing the present invention;

Fig. 2 is an enlarged end elevation of one good form of means for varying the relative inclination of the carpet or rug and rubbing surface of 75 the platen;

Fig. 3 is a front elevation, with parts in section, showing more particularly the details of the platen mounting for angular adjustment;

Fig. 4 is a sectional detail showing one good 80 form of means for driving the platen actuating mechanism;

Fig. 5 is an enlarged section on the line 5—5 of Fig. 3;

Fig. 6 is a modified form of the platen mounting for alternately increasing and decreasing the pressure of the rubbing surface against the pile 85 of the carpet or rug during the movement of the platen;

Fig. 7 is a view similar to Fig. 6, wherein the platen is under spring control for yieldingly increasing and decreasing the platen pressure; and

Fig. 8 is an enlarged sectional detail of a carpet or rug showing in the lower portion thereof the pile surface formed of twisted tufts and in the upper portion thereof the separated and interlocked or felted fibers of adjacent tufts as a result of the machine operation.

As hereinbefore noted, the pile tufts of the carpet or rug are first subjected to a heating and 100

moistening mechanism and while the carpet or rug is in a steam saturated condition the run of the carpet which is unsupported by backing is acted upon by the rubbing surface of the platen.

5 The machine frame for supporting the operating parts may be of any suitable character and as shown in Fig. 1 it consists of the standards 1 surrounded by a member frame 2 and held in appropriate relative positions by the ties or girths 10 3 of Fig. 3.

Supported by the machine frame at one end thereof is a guide member 4 constituted as a roller over which the carpet or rug passes from any suitable supply, and at the opposite end of the 15 machine is a roller 5 under which the carpet or rug passes to the means for progressing the fabric through the machine.

As one good form of means for heating and moistening the pile surface of the carpet or rug 20 a steam box or chamber 6 is mounted between the rollers 4 and 5, and within the chamber 6 are the steam pipes 7, having openings 8 which are directed laterally of the steam chamber to avoid projecting the steam directly upon the carpet or rug which might have the effect of discoloring it.

The steam chamber 6 may be supported from the machine frame in any convenient manner and as shown is held in position by hangers 9 which extend under the steam box and have upwardly 30 extending portions formed with hooks, as shown in Fig. 1, to engage the cross bars 10.

The steam box 6 is provided with a perforated plate 11 above the steam pipes and during the machine operation the carpet or rug F passes 35 above the surface 11 which may serve as a support therefor.

In some cases it may be desirable to conduct the steam away from the machine after having performed its heating and moistening function, 40 and to this end the present invention shows a hood 12 mounted above the steam box and having an exit opening 13 for the steam. Water of condensation may be drained from the steam box by any appropriate form of opening.

45 As hereinbefore noted the carpet or rug is progressed through the machine, as indicated in Fig. 1, and as a good form of means to this end a spiked roller 14 engages the carpet or rug at a point remote from the rubbing platen, with the 50 result that the carpet or rug is drawn from its source of supply and the run thereof between the roller 5 and spiked roller 14 is subjected to tension opposite the rubbing platen 41.

In accordance with the present invention, as 55 shown, the rubbing platen 41 is mounted for angular variation with respect to the pile surface of the carpet or rug being treated, and as one good form of means to this end a shaft 17 extends transversely of the machine, Figs. 1 and 3, and 60 affords a support for the associated parts including the platen and its driving mechanism. The shaft 17 may be conveniently supported on brackets 18, one at each side of the machine, which are bolted at 19 to adjustable angle irons 65 20 appropriately secured to the machine frame at each side thereof by the bolts 21 which pass through appropriate slots in one flange of the angle irons, the result being that upon manipulation of the bolts 21 the entire mechanism including the shafts 17 and parts carried thereby 70 may be raised or lowered, and in order to facilitate such adjustment of the angle irons 20 adjusting means such as the threaded bolts 22 may be used.

75 The shaft 17 is mounted for rotative movement

in the bearings 23, Fig. 3, and connected to the shaft 17 at one end thereof is a worm wheel 24 which is engaged by the worm 25 formed on a shaft 26 rotatably mounted in bearings 27 on the brackets 18. Secured to the shaft 26 is the hand wheel 28 whereby the worm and perforce the shaft 17 may be turned or adjusted in desirable position to vary the angular relation between the rubbing face of the platen and the pile surface of the carpet or rug under treatment.

80 Secured to the shaft 17 for rotative movement therewith is the arcuate plate 29 and extending transversely of the machine are the flange beams 33, one at each side of the shaft 17 to provide a space 30 therefor, as indicated in Fig. 5. The flange beams 33 may be conveniently secured to the arcuate plate 29 at one end and have a bearing on the shaft 17 at the opposite end, the construction being such that should the shaft 17 be turned on its axis, by the means hereinbefore described, the flange beams 33 will likewise be turned and as such flange beams 33 afford a support for the rubbing platen operating mechanism, the platen itself will be angularly adjusted relative to the plane of the carpet or rug by the turning movement of the shaft 17.

85 Mounted upon the flange beams 33 are the bearings 34 for the platen operating shafts 16, and as a convenient means for associating the bearings 34 with the flange beams 33 bearing support plates 35 are secured to the flange beams, as indicated in Figs. 3 and 5, and since the flange beams have a recess between the upper and lower flanges thereof filler plates 36 may be secured between the upper and lower flanges of the beams 33, as indicated in Figs. 3 and 5.

90 In the present instance of the invention the rubbing platen is given its oscillatory reciprocating movement by eccentrics, of which there may be any suitable number, two being shown in the 115 present instance, each connected to one of the operating shafts 16.

95 Each of the shafts 16 is provided with an eccentric 37, which is embraced by eccentric straps 38 and provided with side flanges 39 and is held in 120 projections or blocks 40 secured to the adjacent face of the platen 41.

100 Extending over the eccentrics and preferably over the flanges 39 of the straps are the retaining plates 42, which serve to hold the eccentrics and rubbing platen in operating relation. If desired, sleeves 43 may be interposed between each of the bearings 34 and eccentrics 37 for securing the latter to their operating shafts 16.

105 The driving means for the eccentrics may be 130 variously contrived, but as shown in the present instance of the invention it comprises the shaft 44, Figs. 1 and 3, mounted in suitable bearings 45 for rotative movement, and the bearings 45 are secured to the flange beams 33, with the result 135 that as the shaft 17 is turned the flange beams and perforce the eccentric operating mechanism will likewise move. The operating shafts 16 are actuated from the shaft 44, in the present instance, by cooperating bevel gears 46, Fig. 1.

140 It will thus be seen that the flange beams 33 and shaft 17 constitute an adjusting mechanism, which carries the eccentric operating mechanism and platen, so that upon rotation of the shaft 17 the platen may be swung about the shaft 17 as a 145 centre to vary its angular relation to the carpet or rug being treated.

150 In order that the mechanism for varying the angular relation of the platen with the pile surface of the carpet or rug may be secured in ad-

justed position, the arcuate plate 29 is provided with a slot 31 through which passes a bolt 32 extending through the bearing bracket 18, with the result that by loosening the bolt 32 and turning the hand wheel 28 the angular relation between the platen and plane of the carpet and rug may be changed and then the parts held in their new position by the clamping bolt 32.

The shaft 44 for operating the eccentrics and platen may be driven through any preferred form of mechanism, but as shown in the present instance of the invention, Fig. 4, the shaft 17 has loosely mounted thereon the driving pulley 47 which is held in place by a cap piece 48. The hub portion of the driving pulley 47 is elongated, as indicated in Fig. 4 at 49 and splined to the hub portion 49 is the gear 50 which is in driving engagement with the gear 51 secured to the shaft 44, the construction being such that upon rotating the pulley 47 on the shaft 17 the gear 50 will be rotated and through its driving connection with the gear 51 will impart rotative movement to the shaft 44 and cause the platen to be given its rubbing movement regardless of the position of the platen.

In the construction so far described the rubbing face of the platen 41 is at right angles to the axis of its operating shaft 16 and by changing the angular relation of the platen with respect to the carpet or rug the action of the platen will vary in effect on the pile forming tufts with an alternate increasing and decreasing pressure. In the modification indicated in Fig. 6 the rubbing face of the platen is angularly related to its operating shaft 16 with the result that on actuation of the eccentrics to impart the oscillatory reciprocating movement to the platen the latter will act with an alternate increase and decrease of pressure upon the pile surface of the carpet or rug, a condition which serves first to separate the fibres of the pile forming tufts, and second to interlock or felt together the fibres of adjacent tufts. While this condition may be carried into effect whether the platen is moved in a direction to untwist the pile forming tufts or otherwise, it is more conducive to the separation of fibres of the tufts by causing the platen to move in a direction to remove part or all of the twist in the pile forming tufts.

In the modification shown in Fig. 7 the platen 41^x is under the influence of a spring or other yielding means to permit the rubbing surface of the platen to yield during the movements thereof.

As shown, the rubbing surface of the platen is pivoted at 52 to a part 53 connected with the eccentric bearing and at its lower portion the rubbing surface of the platen is under the influence of a spring 54, normally acting to move the lower portion of the platen towards the pile surface being treated. As shown, one end of the spring 54 bears upon a projection or bracket 55 secured to the eccentric bearing, while the other end of the spring bears upon a projection 56 connected with the platen 41^x, and in order to limit the action of the spring upon the platen a rod 57 extends through the spring and has one end connected to the platen and its other end provided with an adjusting nut to limit the action of the spring.

In each of the constructions shown the platens are so operated that the rotating and reciprocating movement imparted to the platen will serve to remove the twist from the yarns 58 and effect a felting of the fibres at the ends of these yarns together, as will be apparent upon examining the upper tufts of the fabric shown in Fig. 8.

In the form of fabric illustrated the tuft forming yarns 58 are looped about the upper wefts 59 and these upper wefts are bound to the lower wefts 60 by chain warps 61, the upper and lower wefts being separated by the stuffer warps 62.

The speed at which the platen operating shafts 16 are rotated is preferably such that the platen will exert repeated rubbing movement upon each portion of the fabric being advanced from the lower roller 5 to the upper spiked roller 14, and the pressure which the platen exerts upon the face of the pile may be varied as desired.

It will be understood from the foregoing that practically any type of carpet or rug having a pile surface may have the appearance of the pile greatly improved by treating the same in accordance with the disclosure of the present invention.

The rubbing surface of the platen may be formed by the surface of the platen itself or, as shown in the drawings, the rubbing face of the platen may comprise a covering fabric such for instance as rubber or the like.

What is claimed is:—

1. In a machine for finishing the pile surface of carpets and rugs, the combination of a steaming chamber for raising, conditioning, heating and moistening the pile surface of the carpet or rug, a rubbing platen having a rubbing surface, means for bodily moving the platen while in contact with this pile surface to first separate the fibres of the pile forming tufts and second to permanently intermesh or felt together the end portions of the separated fibres while in a heated and moist condition to eliminate row effect and grinding through of the backing fabric, and means for changing relatively the plane of the carpet or rug and the rubbing surface of the platen that the latter may act upon the pile surface with varying effect.

2. In a machine for finishing the pile surface of carpets and rugs, the combination of pile heating and moistening means, a rubbing platen having a rubbing surface to act upon the pile forming tufts, means for causing the rubbing surface to move in contact with the pile forming tufts to first separate the fibres of the tufts and second to permanently intermesh or felt together fibres of adjacent tufts, and means for progressing and tensioning an unsupported run of the carpet or rug in yielding contact with the rubbing surface of the platen due to the tension of the carpet or rug while the pile surface is in a moist and heated condition.

3. In a machine for finishing the pile surface of carpets and rugs, the combination of pile heating and moistening means, a rubbing platen having a rubbing surface to act upon the pile forming tufts, means for causing the rubbing surface to move in contact with the pile forming tufts to first separate the fibres of the tufts and second to permanently intermesh or felt together fibres of adjacent tufts, and means for progressing an unsupported run of the carpet or rug by and in yielding contact with the rubbing surface of the platen while the pile surface is in a moist and heated condition, and means for changing relatively the plane of the unsupported run of the carpet or rug and the plane of action of the rubbing surface for varying the rubbing effect upon the pile surface.

4. In a machine for finishing the pile surface of carpets and rugs, the combination of pile heating and moistening means, a rubbing platen having a rubbing surface to act upon the pile forming

tufts, means for causing the rubbing surface to move in contact with the pile forming tufts to first separate the fibres of the tufts and second to permanently intermesh or felt together fibres of adjacent tufts, and means for guiding and feeding a portion of the unsupported carpet or rug in a stretched condition opposite the rubbing surface that the degree of tension on the carpet or rug alone may retain the carpet or rug in yielding engagement with the surface of the rubbing platen.

5. In a machine for finishing the pile surface of carpets and rugs, the combination of means for heating and moistening the pile surface, a platen having a rubbing surface, means for operating the platen to effect a rubbing action upon the pile forming tufts for separating the fibres thereof and interlocking or felting the fibres of adjacent tufts together permanently, and means for varying the plane of action of the platen upon the pile surface to alternately increase and decrease its pressure upon the pile surface during the platen movement.

6. In a machine for finishing the pile surface of carpets and rugs, the combination of means for heating and moistening the pile surface, a platen having a rubbing surface, means for operating the platen to effect a rubbing action upon the pile forming tufts in a direction to remove twist therefrom and for separating the fibres thereof and interlocking or felting the fibres of adjacent tufts together permanently, and means for varying the plane of action of the platen upon the pile surface to alternately increase and decrease its pressure upon the pile surface during the platen movement.

7. In a machine for finishing the pile surface of carpets and rugs, the combination of means for heating and moistening the pile forming tufts to condition them, a platen having a rubbing surface to act upon the pile forming tufts, means for imparting a movement to the platen to first untwist and separate the fibres of the pile forming tufts and second to interlock or felt together the end portions of the fibres in adjacent tufts, and means for supporting the platen so that its pile engaging surface is at an angle to the pile surface that the pressure of the rubbing surface of the platen upon the tufts may increase and diminish during the movement of the platen.

8. In a machine for finishing the pile surface of carpets and rugs, the combination of means for heating and moistening the pile surface, a platen having a rubbing surface inclined to the plane in which the platen is moved to vary the pressure on the pile surface during the rubbing movements of the platen, and means for imparting bodily movements to the platen to first separate the fibres of the pile forming tufts and second to permanently interlock or felt the fibres of adjacent tufts.

9. In a machine for finishing the pile surface of carpets and rugs, the combination of means for heating and moistening the pile forming tufts of a carpet or rug, a platen having an oscillatory reciprocating movement and provided with a pile rubbing surface inclined to the plane in which the platen moves to vary the rubbing pressure upon the pile during the movement of the platen, and means for operating the platen to first separate the fibres of the pile forming tufts and second to permanently interlock the end portions of the fibres of adjacent tufts to eliminate "row" effects and increase the coverage of the backing fabric.

10. In a machine for finishing the pile surface of carpets and rugs, the combination of means for heating and moistening the pile forming tufts of a carpet or rug, a platen having an oscillatory reciprocating movement and provided with a pile rubbing surface yieldingly supported in a position inclined to the plane in which the platen moves to vary the rubbing pressure upon the pile during the movement of the platen, and means for operating the platen to first separate the fibres of the pile forming tufts and second to permanently interlock the end portions of the fibres of adjacent tufts to eliminate "row" effects and increase the coverage of the backing fabric.

11. In a machine for finishing the pile surface of carpets and rugs, the combination of means for heating and moistening the pile forming tufts of a carpet or rug, a platen having an oscillatory reciprocating movement and provided with a pile rubbing surface inclined to the plane in which the platen moves to vary the rubbing pressure upon the pile during the movement of the platen, yielding means acting upon the rubbing surface of the platen to permit automatic variation in the inclination of said surface during the platen movement and means for operating the platen to first separate the fibres of the pile forming tufts and second to permanently interlock the end portions of the fibres of adjacent tufts to eliminate "row" effects and increase the coverage of the backing fabric.

12. In a machine for finishing the pile surface of carpets and rugs, the combination of means for heating and moistening the yarns forming the pile, a rubbing member for the pile surface of the carpet or rug, shafts for supporting the rubbing member for angular adjustment and sliding movement over the face of the pile in a direction to first untwist the pile yarns and second to interlock or felt the fibres of the yarns together while in a heated and moist condition, and a frame for supporting said shafts for angular adjustment about a central axis extending at right angles to said shafts.

13. In a machine for finishing the pile surface of carpets and rugs, the combination of means for heating and moistening the yarns forming the pile, a rubbing member for the pile surface of the carpet or rug, shafts for supporting the rubbing member for angular adjustment and sliding movement over the face of the pile in a direction to first untwist the pile yarns and second to interlock or felt the fibres of the yarns together while in a heated and moist condition, a frame for supporting said shafts for angular adjustment about a central axis extending at right angles to said shaft, and means movable about said central axis for driving said shafts.

14. In a machine for finishing the pile surface of carpets and rugs, the combination of means for heating and moistening the yarns forming the pile, a platen for rubbing the pile surface of the carpet or rug, shafts provided with eccentrics for operating the platen in contact with the face of the pile to first untwist the pile yarns and second to interlock or felt the fibres of the yarns together while in a heated and moist condition, and a frame for supporting the shafts for angular adjustment about a central axis extending at right angles to the shafts.

15. In a machine for finishing the pile surface of carpets and rugs, the combination of a steam chamber, means for feeding and guiding a carpet or rug through said chamber and presenting a

tensioned and unsupported run thereof outside of said chamber, a platen having a pile rubbing surface located between the feeding and guiding means to act upon the unsupported tensioned run of the carpet or rug so that the tension of the carpet or rug alone will yieldingly hold the carpet or rug in contact with the rubbing surface of the platen, and means for moving the platen in an

oscillatory reciprocating path in contact with the pile to first separate the fibres of the pile forming tufts and second to permanently interlock or felt the ends of the fibres in adjacent tufts to eliminate "row" effect and increase the coverage of the backing fabric. 80
